US00D746801S

(12) **United States Design Patent**
Pan(10) **Patent No.:** **US D746,801 S**
(45) **Date of Patent:** **** Jan. 5, 2016**(54) **CASE FOR MOBILE PHONE**4,536,979 A 8/1985 Parkinson
4,896,787 A 1/1990 Delamour et al.
4,993,866 A 2/1991 Sugihara et al.(71) Applicant: **Superior Communications, Inc.**,
Irwindale, CA (US)

(Continued)

(72) Inventor: **Jason Pan**, Los Angeles, CA (US)**FOREIGN PATENT DOCUMENTS**(73) Assignee: **Superior Communications, Inc.**,
Irwindale, CA (US)EP 1096759 5/2011
JP 2008-018637 1/1996(**) Term: **14 Years**

(Continued)

(21) Appl. No.: **29/468,180****OTHER PUBLICATIONS**(22) Filed: **Sep. 26, 2013**Internet Publication, Jerrod H., "SBS Innovations iShok 5G Video",
Nov. 17, 2006; 4 pages.(51) **LOC (10) Cl.** **14-03**

See application file for complete search history.

(56) **References Cited**

FIG. 1 is a front perspective view of a case for mobile phone showing my new design;
FIG. 2 is a front view of the case for mobile phone;
FIG. 3 is a rear view of the case for mobile phone;
FIG. 4 is a left side view of the case for mobile phone;
FIG. 5 is a right side view of the case for mobile phone;
FIG. 6 is a top view of the case for mobile phone; and,
FIG. 7 is a bottom view of the case for mobile phone.

The dot-dash broken lines in FIGS. 3, 4, 5, 6, and 7, represent a boundary of the claimed design. The dash-dash broken lines depict unclaimed subject matter. The broken lines and unshaded surfaces bounded by broken lines form no part of the claimed design.
